US0D1073200S

(12) **United States Design Patent** (10) **Patent No.:** **US D1,073,200 S**
(45) **Date of Patent:** **** Apr. 29, 2025**

(54) **PET FEEDER**

(71) Applicant: **Xiaohui Ying**, Zhejiang (CN)

(72) Inventor: **Xiaohui Ying**, Zhejiang (CN)

(**) Term: **15 Years**

(21) Appl. No.: **29/925,053**

(22) Filed: **Jan. 22, 2024**

(30) **Foreign Application Priority Data**

Dec. 15, 2023 (CN) 202330826654.X

(51) **LOC (15) Cl.** **30-07**

(52) **U.S. Cl.**

USPC **D30/122; D30/121**

(57) **CLAIM**

The ornamental design for a pet feeder, as shown and described.

DESCRIPTION

FIG. 1 is a front and top view of a pet feeder showing my new design;

FIG. 2 is a rear and bottom view thereof;

FIG. 3 is a front view thereof;

FIG. 4 is a rear view thereof;

FIG. 5 is a left view thereof;

FIG. 6 is a right view thereof;

FIG. 7 is a top plan view thereof; and,

FIG. 8 is a bottom plan view thereof.

(Continued)

The broken lines shown in the drawings illustrate portions of the pet feeder that form no part of the claimed design.

1 Claim, 8 Drawing Sheets
